(57) **CLAIM**

The ornamental design for a multi-use baby cover, as shown and described.

DESCRIPTION

FIG. 1 is a perspective view of the multi-use baby cover showing my new design as it might be used draped over the head of a nursing mother. The broken line illustration of a nursing mother is not part of the design.

FIG. 2 is a top view thereof.

FIG. 3 is a front view thereof showing a finished boarder comprising a fabric pattern that contrasts with the fabric pattern of the remainder of the multi-use baby cover.

FIG. 4 is a left side view showing an opening in the left side seam through which the nursing mother's head may pass.

FIG. 5 is a right side view thereof.

FIG. 6 is a bottom view thereof.

FIG. 7 is a back view thereof.

FIG. 8 is another perspective view of the multi-use baby cover as it might be used by a nursing mother.

FIG. 9 is a perspective view of the multi-use baby cover as it might be draped over a baby carrier. The broken line illustration of the baby carrier is not part of the design; and,

FIG. 10 is a perspective view of the multi-use baby cover as it might be draped over a baby stroller. The broken line illustration of the baby stroller is not part of the design.

The broken line illustration of stitching that appears near the edge of the contrasting border in FIGS. 1, 3, and 7–10 is not part of the design.
